CANAPE TOOTHPICK HOLDER

Biagio P. Melaragno, Cranston, R.I., assignor of one-half to Vincent M. Del Gigante, Cranston, R.I.

Filed Oct. 2, 1959, Ser. No. 57,773

Term of patent 3½ years

(Cl. D44—24)

Fig. 1 is a perspective view of a canape toothpick holder, showing my new design, the elements being assembled on a lemon form shown in broken line for illustrative purposes, with toothpicks in broken lines for like purposes;

Fig. 2 is an exploded perspective view of the elements.
I claim:

The ornamental design for a canape toothpick holder, as shown and described.
